ACOUSTICAL COVER FOR A TELETYPE MACHINE

Frederick M. Ingram, Bethlehem, Pa., assignor to Bur-
roughs Corporation, Detroit, Mich., a corporation of
Michigan

Filed Feb. 17, 1969, Ser. No. 15,808

Term of patent 14 years

Int. Cl. D14—03

U.S. Cl. D26—14

Fig. 1

Des. 218,752

PAGE 2

Fig. 2

Fig. 3

FIG. 1 is a top, front and side perspective view of my new design of an acoustical cover for a teletype machine;

FIG. 2 is a rear perspective view of the acoustical cover for a teletype machine; and

FIG. 3 is another view of the top, front and side perspective of the cover with the top cover extended.

I claim:

The ornamental design for an acoustical cover for a teletype machine, as shown.
